Primary Examiner — Richard Kearney*Assistant Examiner* — Benjamin M Weeks(74) *Attorney, Agent, or Firm* — Alexander Chen, Esq.(57) **CLAIM**

The ornamental design for a loupe set, as shown and described.

DESCRIPTION

FIG. 1 is a top perspective view of the left side of a loupe set showing my new design;

FIG. 2 is a bottom perspective view thereof;

FIG. 3 is a left side view thereof;

FIG. 4 is a right side view thereof;

FIG. 5 is a front side view thereof;

FIG. 6 is a back side view thereof;

FIG. 7 is a top side view thereof;

FIG. 8 is a bottom side view thereof; and,

FIG. 9 is a perspective view of loupe set showing both the left and right loupes in an environment of use.

The broken lines are included to show environmental structure and form no part of the claimed design.
